HIBACHI STOVE

George J. Strauss, 6606 10th Ave.,
Los Angeles, Calif. 90043

Filed Jan. 21, 1970, Ser. No. 21,024

Term of patent 3½ years

Int. Cl. D7—04

U.S. Cl. D81—10

Fig. 1.

Fig. 2.

Fig. 3.

FIG. 1 is a front perspective view of a hibachi stove embodying my new design;

FIG. 2 is a rear elevational view of the same;

FIG. 3 is a side elevational view of one side. The opposite side is substantially identical.

I claim:

The ornamental design for a hibachi stove, substantially as shown and described.
